UNITED STATES PATENT OFFICE.

MAXMILIAN ERNST, OF CLEVELAND, OHIO.

DESIGN FOR A BOX-COVER.

SPECIFICATION forming part of Design No. 24,391, dated June 11, 1895.

Application filed May 9, 1895. Serial No. 548,775. Term of patent 7 years.

To all whom it may concern:

Be it known that I, MAXMILIAN ERNST, a citizen of the United States, residing at Cleveland, in the county of Cuyahoga and State of 5 Ohio, have invented and produced a new and original Design for Box-Covers, of which the following is a specification, reference being had to the accompanying drawings, forming a part thereof.

10 Figure 1 is picture of a box-cover made according to my design. Fig. 2 is a central vertical section of the cover applied to the box.

15 The leading feature of my design consists in such a contour of the external surfaces of the box-cover as to present to the eye the ef-

feet of the representation of a horn and a woman sitting or reclining upon the horn.

In Fig. 2 of the drawings, *a* designates the box-proper, and *b*, the cover.

What I claim is—

20 The design for a box-cover herein shown and described.

In testimony whereof I sign this specification, in the presence of two witnesses, this 6th day of May, 1895.

MAXMILIAN ERNST.
